UNITED STATES PATENT OFFICE.

EUGENE L. JACQUES, OF WATERBURY, CONNECTICUT.

DESIGN FOR A HOLDER FOR BOTTLES.

SPECIFICATION forming part of Design No. 26,729, dated March 9, 1897.

Application filed January 28, 1897. Serial No. 621,104. Term of patent 14 years.

To all whom it may concern:

Be it known that I, EUGENE L. JACQUES, a citizen of the United States, residing at Waterbury, in the county of New Haven and State of Connecticut, have invented and produced a new and original Design for a Holder for Ginger-Ale and Like Bottles, of which the following is a specification, reference being had to the accompanying drawing, forming a part of this specification, which represents a perspective view of a holder embodying the features of my design.

The design consists of a block A, that simu-

lates ice. In the upper surface of the representation of the block of ice recesses or depressions B are represented. Each depression represents the segment of a hollow cylinder, one end C whereof is contracted.

I claim—

The design for a holder for ginger-ale and like bottles herein shown and described.

EUGENE L. JACQUES.
